GAME BOARD

Jerome J. Donnellon, Butler County, Ohio
(7958 Dimmick Road, Cincinnati, Ohio 45241)

Filed Feb. 6, 1967, Ser. No. 5,735

Term of patent 14 years

(Cl. D34—5)

The figure is a plan view of a game board showing my new design, said board being of conventional thickness and the dominant features of the design reside in the portion shown in full lines.

I claim:

The ornamental design for a game board, as shown and described.
